TESTING APPARATUS FOR SCALE MODELS
OF AERODYNAMIC DUCTS

René Leduc, Vesinet, France

Application August 25, 1951, Serial No. 243,658
In France March 12, 1948

20 Claims. (Cl. 73—147)

1

The present invention relates to a testing apparatus for scale models of aerodynamic ducts, and more particularly to a model-scale duct having an outer shell being the replica of the outer shell of a full-scale duct operating with combustion means.

The present application is a continuation-in-part of the co-pending application Serial No. 80,337, filed March 8, 1949, now abandoned, for "Apparatus for Wind Tunnel Testing of Scale Models of Aerothermodynamic Ducts."

It is an object of the present invention to provide a model-scale duct on a reduced scale in which the effect of the combustion means in the full-scale duct on the flow of air is limited by means operating without combustion.

It is another object of the present invention to provide a wind tunnel equipped with a tunnel balance in combination with the model-scale duct.

It is a further object of the present invention to imitate the loss in pressure suffered by the air under the influence of the combustion means provided in the full-scale duct.

A testing apparatus according to the present invention comprises in its broadest aspect a model-scale duct having an outer shell being the replica of the outer shell of a full-scale duct operating with combustion means arranged within the full-scale duct, the model-scale duct having an entry end and an exit end, means for supporting the model-scale duct in an air stream, and a body having a surface of revolution formed by a curved line, the body being arranged within the model-scale duct substantially coaxially with the same and extending from a point spaced from the entry end of the model-scale duct at least to the exit end thereof so as to form an annular air passage between the model-scale duct and the body, the body being shaped so that at any cross-section perpendicular to the axis of the body the ratio of the cross-sectional area of the annular air passage between the body and the model-scale duct to the total internal cross-sectional area of the duct is equal to the square root of the ratio of the density of heated air at the temperature prevailing at the same axial cross-section in a heated full-scale duct operating with combustion means to the density of air at the prevailing ambient temperature.

Preferably the body has a rounded leading end located substantially at the zone of maximum cross-section of the model-scale duct.

Preferably the body includes a portion having a substantially cylindrical and constant cross-

2

section, the portion being located outside and beyond the exit end of the model-scale duct.

In a preferred embodiment of the present invention, an element, preferably designed as a grid is arranged in front of the leading end of the body, the element restricting the flow of air through the model-scale duct so as to imitate the loss of pressure due to the combustion means operating in the full-scale duct.

Preferably the element is attached to the leading end of the body and disposed perpendicularly to the axis of the model-scale duct.

A testing apparatus according to a preferred embodiment of the present invention comprises in combination, a wind tunnel, a model-scale duct arranged coaxially to the wind tunnel, the model-scale duct having an outer shell being the replica of the outer shell of a full-scale duct operating with combustion means arranged at the largest cross-section of the full-scale duct, the model-scale duct having a variable cross-section increasing from the entry end thereof to a zone of maximum cross-section and decreasing from the zone of maximum cross-section to the exit end of the model-scale duct; balancing means supporting the model-scale duct in the air stream through the wind tunnel, a body rigidly connected to said wind tunnel and having a surface of revolution formed by a curved line, the body being arranged within the model-scale duct substantially coaxially with the same and extending from a point spaced from the entry end thereof so as to form an annular air passage between the model-scale duct and the body, the body being shaped so that at any cross-section perpendicular to the axis of the body the ratio of the cross-sectional area of the annular air passage between the body and the model-scale duct to the total internal cross-sectional area of the duct is equal to the square root of the ratio of the density of heated air at the temperature prevailing at the same axial cross-section in a heated full-scale duct operating with combustion means, to the density of air at the prevailing ambient temperature, and a portion forming part of the body and having a substantially cylindrical constant cross-section, the portion being located outside and beyond the exit end of the model-scale duct.

The novel features which are considered as characteristic for the invention are set forth in particular in the appended claims. The invention itself, however, both as to its construction and its method of operation, together with additional objects and advantages thereof, will be best understood from the following description

of specific embodiments when read in connection with the accompanying drawings, in which:

Fig. 1 is a sectional elevation of a full-scale duct;

Fig. 2 is a sectional elevation of a wind tunnel and a model-scale duct according to the invention; and

Fig. 3 is a modification of the model-scale duct shown in Fig. 2.

Referring now to the drawings and first to Fig. 1, the full-scale duct 1 comprises a divergent entry diffuser 2 and a convergent exhaust nozzle 3, between which the duct is provided at its maximum cross-section with internal means 4, diagrammatically represented, for heating the air flowing through it. Usually, of course, the means 4 comprise fuel burners. The air enters the duct with velocity V_0 and is exhausted after being heated by the means 4 with velocity V_3 , indicated by arrows. The arrows 5 represent the internal pressures experienced by the duct-wall, such pressures being normal to the wall. The areas of a number of cross-sections of the duct are represented by Ω_0 , Ω_1 , Ω'_1 , Ω_2 and Ω_3 . The area Ω_0 at the entry is less than the area Ω_3 of the nozzle exit. Ω_1 is equal to Ω_3 , and Ω'_1 is equal to Ω_2 .

Since Ω_0 is less than $\Omega_1 = \Omega_3$, the axial components of the pressures 5 in the zone $\Omega_0 - \Omega_1$ are unbalanced. Furthermore, the normal pressure 5 at any section such as Ω_2 downstream of the heating zone is less than the corresponding pressure at a section of equal area and circumference, such as Ω'_1 upstream of the heating zone, on account of the increase in velocity imparted to the fluid by expansion downstream of the heating zone. The forward axial components of the pressures in the divergent part of the duct from section Ω_1 to the heater 4 are therefore incompletely balanced by the rearward axial components of the pressure in the convergent part of the duct downstream of the heater. The duct therefore develops a thrust equal to the sum of all the unbalanced forward components of internal pressure, or, more accurately, equal to the integral along the axis of the duct of the axial component of the internal pressure multiplied by the circumference.

Referring now to Fig. 2, the model-scale duct 1' likewise comprising a divergent entry diffuser 2' and a convergent exhaust nozzle 3', is geometrically similar to the full-scale duct of Fig. 1. Coaxially placed therein is a body 6 which extends downstream of the duct as shown at 7 to a mounting 8 such as arms connected to the wind tunnel 12 at a location downstream of the model-scale duct 1' and remote from the duct with which the arms 8 have no physical connection, so that aerodynamic forces experienced by the body 6 are not transmitted to the tunnel balance 9, 10.

The arms 8 cause only a small disturbance in the outflowing air since the arms 8 are disposed at a distance from the model-scale duct 1' which is a multiple of the length model-scale duct 1'. The model-scale duct 1' is pivoted to two links 9 and 10 forming part of the tunnel balance and having their other ends pivoted to a supporting element 13. The link 10 is under the action of a spring 11 connected to a stationary part 14. The spring 11 allows to measure the thrust exerted by the air on the model-scale duct 1'.

The body 6 is so shaped that at any cross-section the cross-sectional area of the annulus 75

between the body and the duct-wall, being the difference between the cross-sectional area Ω of the duct and the cross-sectional area ω of the body is determined by the relation

$$\Omega - \omega = \Omega \sqrt{\frac{\rho'}{\rho}} \quad (1)$$

in which

10 ρ is the density of air at ambient temperature; and

15 ρ' is the density of air at the temperature attained in the full-scale duct at the corresponding cross-section when operating with the heater 4 (see Fig. 1) in action.

The leading end of the body 6 is of rounded form to prevent the generation of turbulence by too abrupt a change of cross-sectional area of the air-passage, and the part of the body extending outside the duct is of cylindrical form for a considerable distance downstream, as is shown in Fig. 2, in which the cross-sectional area ω_3 is indicated as constant downstream of the nozzle-exit. The latter feature ensures that the presence of the body 6, 7 does not modify the character of the air-flow outside the duct and give rise to aerodynamic forces on the model which are unrepresentative of the full-scale arrangement.

In order that the forces experienced by the duct shown in Fig. 2 may correctly represent those experienced by that of Fig. 1, the velocities at corresponding cross-sections, when reduced to the same scale must be inversely proportional to the square-roots of the corresponding air-densities ρ' , and ρ , so that

$$\frac{V'}{V} = \sqrt{\frac{\rho'}{\rho}} \quad (2)$$

40 where V' is the velocity at section Ω in Fig. 2 without heating and V is the velocity, with heating, at the corresponding section of Fig. 1 reduced to model-scale. Further the mass-flow through the duct must be the same in both cases so that the mass-flow with heating across any cross-section Ω of the duct shown in Fig. 1, reduced to model-scale, must be equal to that without heating across the corresponding annular section $\Omega - \omega$, of the duct shown in Fig. 2, so that

$$45 \rho V' (\Omega - \omega) = \rho' V \Omega \quad (3)$$

50 which by substitution from Equation 2 becomes the Equation 1 above-stated.

55 It will also be evident that Equation 2 gives the relation of the velocity V'_0 at the nozzle exit of the arrangement of Fig. 2 to the corresponding velocity V_3 in the arrangement of Fig. 1 reduced to model-scale.

60 Referring now to Fig. 3, a modification of the body 6 of the model-scale duct 1' is shown which is intended to take into account certain differences between the real thrust which is measured and that resulting from calculation.

65 It is easy to show that the thrust coefficient of a tube such as a duct can be expressed in the following form:

$$70 \frac{2}{S} (AW_3 - W_0) \quad (4)$$

in which

S is the surface of a plane,

75 W_3 is the cross-section of the gas at a very large distance downstream of the duct (that is, a real section in case of a full-scale duct, and

the section of the cool air and that of the portion 7 in case of a model-scale duct),
W₀ is the cross-sectional area of the air flow at a very large distance from the entry of the duct, A is equal to

$$\frac{V_3^2 g_3}{V_0^2 g_0} \quad (5)$$

g₃ and g₀ are, respectively, the specific gravities of the air at a very large distance downstream and upstream of the duct.

V₃ and V₀ are, respectively, the velocities of the air flow at the very large distance downstream and upstream of the duct.

The value of A can be derived from the Expression 5 by two measurements of the total pressure downstream and upstream of the duct. However, it can be derived also from the Expression 4 by a measurement of the thrust exerted on the duct in the wind tunnel. Generally the value of A derived from the Equation 4 is smaller than that derived from the Equation 5.

In order to overcome this difficulty a loss of pressure is created within the model-scale duct by providing in the same an element such as a grid 15 which is preferably attached to the leading end of the body 6 and disposed perpendicular to the axis of the model-scale duct 1'. The dimensions of the grid are determined so that the values of the term A derived from Equations 4 and 5 are identical with each other. It can be shown that if this is the case the loss of pressure p₁ - p₂, p₁ and p₂ being the pressures upstream and downstream of the grid, is the same as that caused by the combustion means in the full-scale duct.

It should be noted that the grid 15 has no physical connection with the model-scale duct 1'. A sufficient distance is provided between the edge of the grid 15 and the model-scale duct 1' in order to eliminate any frictional forces which could disturb the measurements of the thrust exerted on the model-scale duct 1' which are measured for instance by means of the wind tunnel balance 9 to 14 shown in Fig. 2.

It will be understood that each of the elements described above, or two or more together, may also find a useful application in other types of testing apparatuses for aerodynamic ducts differing from the types described above.

While the invention has been illustrated and described as embodied in a model-scale duct having an outer shell being the replica of the outer shell of a full-scale duct, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a testing apparatus, in combination, a model-scale duct having an outer shell being the replica of the outer shell of a full-scale duct operating with combustion means arranged within the full-scale duct, said model-scale duct hav-

ing an entry end and an exit end; means for supporting said model-scale duct in an air stream; and a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream.

2. In a testing apparatus, in combination, a model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; and a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream.

3. In a testing apparatus, in combination, a model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; and a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to

the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the zone of maximum cross-section of said model-scale duct.

4. In a testing apparatus, in combination, a model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream; and a portion forming part of said body and having a substantially cylindrical constant cross-section, said portion being located outside and beyond the exit end of said model-scale duct.

5. In a testing apparatus, in combination, a model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the zone of maximum cross-section of said model-scale duct.

5 maximum cross-section of said model-scale duct; and a portion forming part of said body and having a substantially cylindrical constant cross-section, said portion being located outside and beyond the exit end of said model-scale duct.

6. In a testing apparatus, in combination, a model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at a temperature prevailing at the corresponding axial cross-section in a heated full-scale duct operating with combustion means to the density of air at the prevailing ambient temperature of said air stream; and a portion forming part of said body and having a substantially cylindrical constant cross-section being smaller than the maximum cross-section of said body, said portion being located outside and beyond the exit end of said model-scale duct.

7. In a testing apparatus, in combination, a model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the zone of maximum cross-section of said model-scale duct; and a portion forming part of said

body and having a substantially cylindrical constant cross-section being smaller than the maximum cross-section of said body, said portion being located outside and beyond the exit of said model-scale duct.

8. In a testing apparatus, in combination, a model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the zone of maximum cross-section of said model-scale duct; and an element arranged in front of said leading end of said body, said element restricting the flow of air through said model-scale duct so as to imitate the loss of pressure due to the combustion means operating in the full-scale duct.

9. In a testing apparatus, in combination, a model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the

zone of maximum cross-section of said model-scale duct; and an element attached to the leading end of said body, said element restricting the flow of air through said model-scale duct so as to imitate the loss of pressure due to the combustion means operating in the full-scale duct.

10. In a testing apparatus, in combination, a model-scale duct having an outer shell having the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the zone of maximum cross-section of said model-scale duct; and a grid arranged in front of said leading end of said body, said grid restricting the flow of air through said model-scale duct so as to imitate the loss of pressure due to the combustion means operating in the full-scale duct.

11. In a testing apparatus, in combination, a model-scale duct having an outer shell having the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located

substantially at the zone of maximum cross-section of said model-scale duct; and a grid attached to the leading end of said body, said grid restricting the flow of air through said model-scale duct so as to imitate the loss of pressure due to the combustion means operating in the full-scale duct.

12. In a testing apparatus, in combination, a model-scale duct having an outer shell having the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the zone of maximum cross-section of said model-scale duct; and a grid disposed perpendicularly to the axis of said model-scale duct and arranged in front of said leading end of said body, said grid restricting the flow of air through said model-scale duct so as to imitate the loss of pressure due to the combustion means operating in the full-scale duct.

13. In a testing apparatus, in combination, a model-scale duct having an outer shell having the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; means for supporting said model-scale duct in an air stream; a body having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream.

vailing ambient temperature of said air stream, said body having a rounded leading end located substantially at the zone of maximum cross-section of said model-scale duct; and a grid disposed perpendicularly to the axis of said model-scale duct and attached to the leading end of said body, said grid restricting the flow of air through said model-scale duct so as to imitate the loss of pressure due to the combustion means operating in the full-scale duct.

14. A testing apparatus, comprising in combination, a wind tunnel; a model-scale duct arranged coaxially within said wind tunnel, said model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; balancing means supporting said model-scale duct in the air stream through said wind tunnel; and a body rigidly connected to said wind tunnel and having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream.

15. A testing apparatus, comprising in combination, a wind tunnel; a model-scale duct arranged coaxially within said wind tunnel, said model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; balancing means supporting said model-scale duct in the air stream through said wind tunnel; a body rigidly connected to said wind tunnel and having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said duct is equal to the square root of the ratio of the density of heated air at the temperature prevailing at the same axial cross-section in a heated full-scale duct operating with combustion means to the

density of air at the prevailing ambient temperature; and a portion forming part of said body and having a substantially cylindrical constant cross-section, said portion being located outside and beyond the exit end of said model-scale duct and being rigidly connected to said wind tunnel.

16. A testing apparatus, comprising in combination, a wind tunnel; a model-scale duct arranged coaxially within said wind tunnel, said model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; balancing means supporting said model-scale duct in the air stream through said wind tunnel; a body rigidly connected to said wind tunnel and having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the zone of maximum cross-section of said model-scale duct; and a portion forming part of said body and having a substantially cylindrical constant cross-section, said portion being located outside and beyond the exit end of said model-scale duct and being rigidly connected to said wind tunnel.

17. A testing apparatus, comprising in combination, a wind tunnel; a model-scale duct arranged coaxially within said wind tunnel, said model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; balancing means supporting said model-scale duct in the air stream through said wind tunnel; a body rigidly connected to said wind tunnel and having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is

equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the zone of maximum cross-section of said model-scale duct; and a portion forming part of said body and having a substantially cylindrical constant cross-section being smaller than the maximum cross-section of said body, said portion being located outside and beyond the exit end of said model-scale duct and being rigidly connected to said wind tunnel.

18. A testing apparatus, comprising in combination, a wind tunnel; a model-scale duct arranged coaxially within said wind tunnel, said model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; balancing means supporting said model-scale duct in the air stream through said wind tunnel; a body rigidly connected to said wind tunnel and having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the zone of maximum cross-section of said model-scale duct; a portion forming part of said body and having a substantially cylindrical constant cross-section, said portion being located outside and beyond the exit end of said model-scale duct and being rigidly connected to said wind tunnel; and a grid arranged in front of said leading end of said body, said grid restricting the flow of air through said model-scale duct so as to imitate the loss of pressure due to the combustion means operating in the full-scale duct.

19. A testing apparatus, comprising in combination, a wind tunnel; a model-scale duct arranged coaxially within said wind tunnel, said model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; balancing means supporting said model-scale

duct in the air stream through said wind tunnel; a body rigidly connected to said wind tunnel and having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the zone of maximum cross-section of said model-scale duct; a portion forming part of said body and having a substantially cylindrical constant cross-section, said portion being located outside and beyond the exit end of said model-scale duct and being rigidly connected to said wind tunnel; and a grid attached to the leading end of said body, said grid restricting the flow of air through said model-scale duct so as to imitate the loss of pressure due to the combustion means operating in the full-scale duct.

20. A testing apparatus, comprising in combination, a wind tunnel; a model-scale duct arranged coaxially within said wind tunnel, said model-scale duct having an outer shell being the replica of the outer shell of a full-scale duct operating with combustion means arranged at the largest cross-section of the full-scale duct, said model-scale duct having a variable cross-section increasing from the entry end thereof to a zone of maximum cross-section and decreasing from the zone of maximum cross-section to the exit end of said model-scale duct; balancing means supporting said model-scale duct in the air stream through said wind tunnel; a body rigidly con-

nected to said wind tunnel and having a surface of revolution formed by a curved line, said body being arranged within said model-scale duct substantially coaxially with the same and extending from a point spaced from said entry end of said model-scale duct at least to the exit end thereof so as to form an annular air passage between said model-scale duct and said body, said body being shaped so that at any cross-section perpendicular to the axis of said body the ratio of the cross-sectional area of said annular air passage between said body and said model-scale duct to the total internal cross-sectional area of said model-scale duct is equal to the square root of the ratio of the density of heated air at the temperature prevailing at the corresponding axial cross-section in a heated full-scale duct operating with combustion means to the density of air at the prevailing ambient temperature of said air stream, said body having a rounded leading end located substantially at the zone of maximum cross-section of said model-scale duct; a portion forming part of said body and having a substantially cylindrical constant cross-section, said portion being located outside and beyond the exit end of said model-scale duct and being rigidly connected to said wind tunnel; and a grid disposed perpendicularly to the axis of said model-scale duct and attached to the leading end of said body, said grid restricting the flow of air through said model-scale duct so as to imitate the loss of pressure due to the combustion means operating in the full-scale duct.
